UNITED STATES PATENT OFFICE.

EDWARD FINK, OF WAUWATOSA, WISCONSIN, ASSIGNOR TO COMPO-TILE MANUFACTURING CO., OF MILWAUKEE, WISCONSIN, A CORPORATION OF WISCONSIN.

BUILDING CONSTRUCTION.

Application filed June 9, 1922. Serial No. 567,135.

To all whom it may concern:

Be it known that I, EDWARD FINK, a citizen of the United States and resident of Wauwatosa, in the county of Milwaukee and State of Wisconsin, have invented new and useful Improvements in Building Constructions, of which the following is a description, reference being had to the accompanying drawings, which are a part of this specification.

This invention relates to building construction, and more particularly to composition boards, and has for its object to produce a cementitious board which may be effectively employed as a shingle, clapboard, and the like, in place of the usual wooden shingles or clapboards heretofore employed.

A further object of the invention is to provide a board of this character in the body of which is incorporated a reinforcing member such as burlap, metal lath or wire, whereby the strength of the board will be greatly increased.

A still further object of the invention is to provide a board having a recessed edge adapted to overlap an adjacent board which edge may be provided with a readily attachable and detachable securing means, whereby the boards may be caused to closely engage the studding or other members to which they are fastened, as well as the said adjacent boards.

A further object of the invention is to provide a building construction of the character described which will be comparatively inexpensive to manufacture and more efficient in use than those which have been heretofore proposed.

With these and other objects in view which will appear as the description proceeds, the invention consists in the novel details of construction and combinations of parts more fully hereinafter disclosed and particularly pointed out in the claims. In the accompanying drawings in which like numerals designate like parts in all the views;

Figure 1 is a fragmentary side elevational view of a portion of a building showing boards made in accordance with the present invention in place thereon.

Fig. 2 is a vertical sectional view on an enlarged scale taken on the line 2—2 of Fig. 1 looking in the direction of the arrows.

Fig. 3 is a horizontal sectional view, tak-

en on the line 3—3 of Fig. 2, looking down and showing in detail the method of fastening the lower or overlapping edges of the boards.

Fig. 4 is a view similar to Fig. 1 illustrating a somewhat modified form of the construction, wherein a butt joint is provided in place of the overlapping joint.

Fig. 5 is a vertical sectional view on an enlarged scale taken approximately on the line 5—5 of Fig. 4;

Fig. 6 is a vertical sectional view of one of the boards illustrated in Figs. 1, 2, and 3, clearly showing the tapering feature thereof; and

Fig. 7 is a sectional view of a modified form of the invention.

Referring more especially to Figs. 1, 2, 3, and 6, the numeral 1 indicates the studding or upright members of a building to which are secured the clapboards 2. These said boards in the present instance are composed of cementitious material commonly known as Sorel's cement or magnesite cement, which consists of calcined magnesia mixed with varying amounts of inert matter, such as silica, wood fiber, and the like, to which mixture may be added any suitable coloring matter, as well as a solution of magnesium chloride, which causes the whole to set into a stone-like mass.

In making these boards according to the present invention a sheet or strip or reinforcing material 3, such for example, as metal lath or woven wire or other fabric, of suitable dimensions, is placed within a mold and a mixture such as above described is introduced therein, so that the said reinforcing material is completely covered thereby and firmly incorporated in the body of the board. If the usual shingle or clapboard effect is to be produced, one surface of the board is tapered as at 4, so that one edge 5 thereof, which will constitute the upper edge when the board is in place, will approximate a feather edge, while the opposite edge 6, will be several times the thickness of the edge 5.

The edge 6 is cut away as at 7, to provide a recess extending the full length of the board, which is adapted to receive the upper edge 5 of the board below, as is clearly illustrated in Fig. 2. This construction provides a depending tongue 8, which overlaps the feather edge 5 of the board below, thereby

giving the usual shingle or clapboard effect when the boards are in position.

In order to hold these boards in place they are provided with a plurality of metal tongues 10, which are embedded in the cementitious body portion along the lower edge of the board. These tongues are preferably shaped substantially as shown in Fig. 2, and the lower free portions 11 thereof, extend into the recess or cut away portion 7, in substantial alinement with the rear face 12 of the board. The said tongues extend into the said recess, for say only $\frac{1}{2}$ to $\frac{1}{2}$ its depth, so that they no wise interfere with the upper edges of the lower boards.

The said tongues, preferably made of spring metal, are adapted to engage metal straps or socket members 13, secured to the studding or joists 1, by means of screws or other suitable fastenings 14, as is clearly indicated in Figs. 1 and 3.

When one board is fastened to the studding or wall the metal strips are fastened to the studding or wall immediately above the narrow or feather edge 5 of the board, so that the metal tongues of the next board engage these strips and the upper board upon being forced downward into place is drawn tightly against the upper edge of the board below. This is highly important especially in roofing, as it effectually prevents any raising up or buckling of the board. In practice it is advisable to apply some fresh cement to the recessed edge of the board before putting same into place, the cement upon hardening effectually unites one board to the other, thus preventing any rain or snow from entering beneath the boards.

This form of fastening is far superior to securing the boards tightly by means of nails or screws, as it allows for considerable shrinking or warping of the rigid members without danger of cracking the boards. The uppermost as well as the lowermost board in a wall must generally be fastened by nailing or screwing and to permit this a plurality of perforations 9 are provided adjoining the feather edge of the board through which nails or other means of fastening may be placed. While the board is constructed to permit nailing, the perforations are nevertheless desirable as all danger of cracking the board through nailing is eliminated.

The method of employing the present invention will be clear from the foregoing, but it may be briefly summarized as follows:

The boards being made in suitable lengths up to say four feet or more, are applied to the studding or joists 1 with their flat rear surface 12 in engagement therewith, and the lowermost board is secured in position by means of nails or other suitable fastening members passing through the holes or per-

forations 9 and entering the said studding or joist.

The lower portion 11 of the tongue members 10 of the next succeeding board is inserted in the strap members 13, which are secured to the studding 1, whereupon the upper edge of the second board may be secured thereto by means of nailing it to the said studding. The tongue portion 8 of the upper board will overlap the feather edge 5 of the lower board to any desired predetermined extent and after all the boards are in place a building construction will result which will have all of the appearances of the usual clapboard or shingle construction. Furthermore inasmuch as the material from which the boards are made is of a fire and water proof nature a construction will result which is exceedingly durable and comparatively safe.

In the form of the invention illustrated in Figs. 4 and 5 instead of providing an overlapping joint the boards are not tapered, so that the lower edges 15 thereof will abut the upper edges 16 of the lower boards, and thus produce a flush joint. The construction, in other respects, is the same as that disclosed in Figs. 1, 2, 3, and 6, and need not be repeated.

It is obvious, of course, that these boards may be made in any desired sizes and that they may be employed either as clapboards or on the siding of the building, or as shingles for the roof, as shown in Fig. 7 in which the cut away portion 7' is of greater length.

It is also obvious that those skilled in the art may vary the precise construction as well as the arrangement of the parts without departing from the spirit of the invention, and therefore it is not wished to be limited to the above disclosure except as may be required by the claims.

What is claimed is:

1. A composition board for building construction comprising a fire and waterproof cementitious body portion having a reinforcing member incorporated therein, said body portion having opposed flat faces and being tapered to provide a relatively thin edge, and a relatively thick edge disposed opposite thereto, said thick edge being recessed to receive the thin edge of an adjacent board, the parts being so proportioned that said thin edge will occupy only a portion of said recess.

2. A composition board for building construction comprising a cementitious body portion having a reinforcing member incorporated therein, and provided with one thin edge, the opposite edge of said board being provided with means substantially flush with the surface of the board adapted to readily engage and disengage a securing means rigid with a portion of the building.

3. A composition board for building construction comprising a fire and waterproof cementitious tapered body portion having a 15
5 fabric reinforcing member incorporated therein, and provided with a thin edge, the thicker edge of said body portion being recessed to receive the thin edge of an adjacent board and a retaining member rigid with a portion of the building and provided with a 20
10 tongue member positioned within said recess adapted to readily engage and disengage 25
said retaining member.

4. A composition board for building construction comprising a fire and waterproof

cementitious tapered body portion having a 15
metallic fabric reinforcing member incorporated therein, and provided with perforations adjacent its thinner edge adapted to receive fastening means, the thicker edge of said body portion being recessed to receive a retaining member rigid with a portion of the building and provided with a tongue member positioned within said recess adapted to readily engage and disengage 20
said retaining member.

In testimony whereof, I affix my signature.

EDWARD FINK.
